UNITED STATES PATENT OFFICE.

HENRY E. LORENTZ, OF BALTIMORE, MARYLAND.

CORD-HOLDER.

947,111.

Specification of Letters Patent. Patented Jan. 18, 1910.

Application filed December 9, 1907. Serial No. 405,765.

To all whom it may concern:

Be it known that I, HENRY E. LORENTZ, a citizen of the United States, residing at Baltimore city, State of Maryland, have 5 invented certain new and useful Improvements in Cord-Holders, of which the following is a specification, reference being had therein to the accompanying drawing.

This invention relates to cord holders 10 especially adapted for use with the flexible conductors or cords used with pendent electric lights, telephone receivers and the like, for adjusting the height of the instrument or length of the cord by forming therein a 15 readily variable loop.

In the accompanying drawings, Figure 1 is a side view of my device with the cord in place and held thereby. Fig. 2 is a like view with the cord so far released that it 20 may be readily slipped for adjustment. Fig. 3 shows a view, looking from the right in Fig. 1 the cord being omitted. Fig. 4 is a view analogous to Fig. 3, showing a modification in which two holding devices are 25 employed. Fig. 5 is a view similar to Fig. 1, showing also two holding devices.

In these views, A represents the cord to be held and B the holding device, which for purposes of illustration is shown in Figs. 30 1, 2, 3, as formed, from a one-piece oblong rectangular block having the angle at its ends slightly rounded, by cutting the block through from side to form a passage E and a communicating passage or opening C of 35 such size and form as to leave, at what is shown as the lower end of the block, a body portion with two comparatively thin flat arms D, D' upon opposite sides of the opening C. The material of the block is resil- 40 ient, wood being sometimes employed, and the form and width of the passage E are such that by pressing the arms D, D' toward each other it may be closed. If the arms be equal and homogeneous in character both 45 arms spring equally, but this is not indispensable. The passage E being thus closed, as shown in Fig. 2, the parts above the opening C, upon opposite sides of the passage thus closed, are bored through to form pas- 50 sages F F' somewhat larger than the cord to be used. The body at the opposite end of the block is also bored to form a pas- 55 sage G in which the cord to be used will fit closely and be frictionally held with com- paratively slight force. The entrances to the bored passages are preferably reamed

to facilitate inserting the cord. If now a suitable cord A be inserted and drawn out more or less from the opening C, as at C', it will be bent somewhat sharply across the 60 passage E when the latter is allowed to open under the resilient action of one or both arms, which throws the two passages F F' out of alinement. The cord is then securely held although it otherwise slides 65 freely in the passage, but obviously it may be instantly released, by pressing the walls D, D' toward each other with the hand, so that the loop may be readily varied.

Fig. 4 shows two devices B', B² like that 70 already described, (except that the frictionally holding cord passage is omitted,) secured together by rivets or the like, one being first turned end for end. In this form both ends of the loop portion of the cord 75 are held by similar devices. Fig. 5 shows a different way of duplicating the holding means, the device being in effect two identical devices like that of Figs. 1, 2, 3, formed in opposite ends of a longer block B². As 80 shown, the frictionally holding cord passage is retained, as shown at G, two loops being formed. Neither the presence of this passage nor its utilization if present is indispensable. In any of the devices, the 85 length of cord lying in the passage E and the abruptness of bending depends upon both the width and the inclination of the pas- 90 sage. It may also be observed that what- ever the inclination, the larger cord passages are readily bored when the parts are pressed together as in Fig. 2 since the material is then practically continuous, and still fur- 95 ther, it is obvious that the exact construc- tion shown need not be followed.

What I claim is:

1. In devices of the class described, the combination of a member provided with a passage in which a cord may be held, of a coacting member provided with an analogous non-alining passage and secured to the first in position to receive in its passage a portion of a cord at some distance from the portion lying in the passage of the first member, one of said members being adapted 100 to offer yielding resistance to bringing the two passages into alinement.

2. In devices of the class described, the combination with a member having at two widely separated points, passages in which 110 a cord may lie with its intermediate portion free, of a second resilient member rigidly

- connected at one end to the first member and having a cord channel normally at one side of a straight line between said passages and in position to engage a cord at a point some 5 distance longitudinally from each of said passages, said second member being adapted to yieldingly resist force tending to move its channel toward alinement with the said passages; whereby a cord passing through 10 said passages and channel is bent laterally and held without shearing action.
3. In devices of the class described, the combination with a member having at widely separated points passages in which a cord 15 may lie with its intermediate portion approximately in a straight line, of a second resilient member secured to the first, having a cord channel normally inclined to a straight line between said passages and in position 20 to engage said intermediate portion at a substantial distance from said passage, and yieldingly hold in deflected position a cord passing through said passages and channel.
4. A cord holder having two approximately parallel materially unequal resilient arms rigidly connected at one end, one of said arms having at its free end a projection provided with a cord receiving passage and the other having an inwardly extending projection at a substantial distance, longitudinally, from the first projection and provided 30 with a normally non-alining cord receiving passage.
5. A cord holder having a body provided

with a passage adapted for frictionally holding a suitable cord and with two approximately parallel, resilient, material unequal arms extending from said body and having inwardly extending oblique faced projections provided with normally non-alining 35 cord passages normally separated longitudinally with respect to a cord passing therein. 40

6. A cord holder provided with two flat resilient approximately parallel arms having at one end an integral connecting portion provided with a cord passage and having at their free ends oblique faced overlapping projections provided with cord 45 passages adapted to register only when the arms are sprung inwardly. 50

7. A cord holder consisting of a block of resilient material cut through between its ends to form an opening bounded on two opposite sides by thin walls and to form a normally open passage dividing obliquely 55 that portion between said opening and one end of the block, the two parts of said portion being cylindrically bored in an approximately axial direction to form cord passages, and the corresponding opposite end portion 60 being similarly bored, substantially as set forth.

In testimony whereof I affix my signature in presence of two witnesses.

HENRY E. LORENTZ.
